UNITED STATES PATENT OFFICE

JOHN J. McDONALD, OF WEST VIEW, PENNSYLVANIA

DESIGN FOR A TIRE

Application filed October 24, 1929. Serial No. 33,151. Term of patent 7 years.

To all whom it may concern:

Be it known that I, JOHN J. McDONALD, citizen of the United States, residing at 176 Highland Avenue, West View, in the county of Allegheny and State of Pennsylvania, have invented a new, original, and ornamental Design for Tires, of which the following is a specification, reference being had to the accompanying drawing, forming part hereof, in which—

I claim—

The ornamental design for a tire as shown.
In testimony whereof, I have hereunto signed my name.

JOHN J. McDONALD.
